[57] CLAIM

The ornamental design for a child's toy, as shown and
described.

DESCRIPTION

FIG. 1 is a right hand perspective view of a child's toy
embodying the invention;

FIG. 2 is a front elevational view thereof;

FIG. 3 is a top plan view thereof;

FIG. 4 is a bottom plan view thereof;

FIG. 5 is a rear elevational view thereof; and

FIG. 6 is a left side elevational view, the right side
elevational view being a mirror image thereof.
